UNITED STATES PATENT OFFICE.

EDGAR H. CLARK, OF RICHMOND HILL, NEW YORK, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

Application filed December 3, 1923. Serial No. 678,115.

This invention relates to telephone exchange systems, and especially to such systems as employ automatic switching apparatus in the establishment of connections.

5 The object of the invention is to secure a more flexible means of interconnecting telephone lines by an improved arrangement of circuits and controlling apparatus.

A feature of the invention relates to a 10 switching device for extending telephone lines, having a plurality of master control circuits each arranged to exercise a different control over said device, together with means for substituting one master control circuit 15 for the other without disabling the switching device.

By means of this arrangement an increase 20 in the speed is secured in the operation of an automatic switch by a reduction in the number of cooperating parts which function in the selective movement of such a switch. This feature as will be readily seen, is of considerable importance where abnormal traffic conditions infrequently occur. 25 Under these conditions the invention allows the use of a smaller number of selective switches to be used than would otherwise be possible.

Other features and advantages inherent in 30 the invention will become apparent after a consideration of the detailed description.

It has been chosen to illustrate the invention in connection with a line switch of the coordinate type, such as is described in 35 the United States patent of J. N. Reynolds, No. 1,507,140 issued September 2, 1924 and further shown and described in United States patent to S. B. Williams, Jr., No. 1,517,331 issued December 2, 1924. However, 40 the invention is not limited in its application to this particular type of switch as it may be applied to any selector switch which operates in conjunction with a controlling master circuit.

45 Referring to the drawing, Fig. 1 shows a number of subscribers' lines and also a portion of a master control circuit consisting of a number of relays, which in their cooperation determine the selecting movements of the associated switch, at the same time preventing interference between calling lines. This will become apparent from

the detailed description given hereinafter. In this figure are also shown certain of the contacts of a key which is individual to 55 the selective switch. The contacts of this key are shown in their normal or unoperated position.

Fig. 2 illustrates a line switch of the coordinate type, such as is described in the 60 above mentioned United States patents. Fig. 2 also shows the remaining portion of the master control circuit and the remaining contacts of the key partly shown in Fig. 1. 65

Figs. 1 and 2, with Fig. 2 to the right of Fig. 1 show that portion of a telephone system which is sufficient for a complete understanding of the invention.

Subscribers' lines 101, 102, etc. enter the 70 exchange and are multiplied before vertical rows of contacts 201, 202, etc. in the line switch 200. Each calling line has access therefore to the number of horizontal links, as 217, 218, etc. These links are divided 75 into a plurality of horizontal groups, of which two are shown, one group including links 217, 218, another group including links 219, 220. There are as many of these groups of links as conditions require. Outgoing 80 from the line switch 200 are a number of trunks 221, 222, each appearing before all the horizontal links. Every outgoing trunk is therefore accessible to any calling subscriber's line through a number of horizontal links. 85

When a subscriber, as the subscriber at station 150, initiates a call, the vertical group relay 206 operates. This relay corresponds to that particular vertical row 90 of contacts before which the calling line appears. The operation of relay 206 opens the starting circuit for all other calling lines in succeeding vertical groups, thus preventing two subscribers of lines in different vertical groups, for example, subscribers at stations 150 and 151, from simultaneously operating a plurality of vertical magnets, as magnets 210 and 214. Relay 206 closes an operating circuit for relay 208 which locks in series with relay 109 which is common to all vertical groups. When relay 206 operates 95 it opens at its right armature and back contact operating circuits for relays of other

- vertical groups similar to relay 208. Relay 208 also closes an operating circuit for the associated line vertical magnet 210, and closes a circuit to operate a horizontal group 5 relay as relay 111, which in conjunction with relays as 112, 113, etc., controls the selection of an idle horizontal link. The time within which the calling line must be associated with an outgoing trunk is under 10 the control of a pair of slow operating relays 110 and 115. Relay 115 begins to operate as soon as a line and a trunk vertical magnet, as 210 and 215, respectively, have been operated. Since relays 110 and 115 15 supply the operating ground for the horizontal magnets, as 211, 212, etc., they control the time within which the latter magnets must operate and complete connections through the switch 200.
- 20 It will be observed that when relays as 206 and 208 operate as a result of a subscriber initiating a call, no other subscriber, either in the same or a different group can cause the operation of line and trunk vertical magnets, until the first-mentioned subscriber's line has been extended through 25 switch 200. As soon, however, as this connection is completed the control circuit is released by the operation and release of relays 110 and 115 and a second subscriber's line may now be extended through the 30 switch.
- From the foregoing general description it will be apparent that no two calling lines 35 can be connected to the same outgoing trunk since the master control circuit prevents two calling lines from being associated with the same trunk through the same or through different horizontal links.
- 40 If, for any reason, however, it becomes necessary to disconnect the master control circuit without disrupting the operation of switch 200, an emergency key is thrown. The operation of this key results in the 45 rendering ineffective of the master circuit and the substitution therefor of a common control circuit. It will be clear, therefore, that the operation of this key has a tendency to increase the possibility of interference between calling lines, during the time the master controlling equipment is temporarily out of service, but at the same time since the switch is controlled by a few fast operating relays, the functioning of such a switch is 50 more speedy, thus allowing a greater number of connections to be completed in a given time than is possible with the use of the master control circuit.
- An arrangement such as that shown in 55 the drawing provides for greater flexibility since it combines the features of a non-interfering selective switch with a means for rendering such a switch more speedy in its operation when conditions demand.
- 60 For the purpose of illustrating the in-

vention, a detailed description will be given first, of the manner in which a connection is completed under normal conditions, that is, with the emergency key unoperated; and second, of a connection completed with the 70 same key operated.

Normal operation.

When one of a group of subscribers, as the subscriber at station 150, removes his receiver, the line relay 103 operates from battery through its winding, right outer armature and back contact of relay 104, ring side of the calling line, through the calling subscriber's loop to the tip side of the line, 80 right inner armature and back contact of relay 104 to ground through the low resistance relay 106 which operates. The operation of relay 103 closes a circuit for relay 206, which, together with relays 207 and 208 is 85 individual to the particular vertical group of contacts 201 of switch 200, in which the calling line terminates. This circuit is as follows: battery, through the winding of relay 206, left armature and contact of relay 207, conductor 159, right hand contact 108 of the emergency key, right outer armature and front contact of relay 103, upper contact 105 of the emergency key to ground at the left armature and contact of relay 107. If 90 a subscriber, whose line terminates in a different vertical group of contacts, as group 202, should now initiate a call, connection of his line through switch 200 would be blocked, since the operating circuit of the 95 associated control relay 223 is opened at the right armature and back contact of relay 206. Relay 206 in operating completes a circuit from battery, through the left winding of relay 208, right front contacts of relay 206, conductor 154, to ground through the contacts of relays 109 and 110.

When relay 208 operates, it closes a locking circuit for itself from battery through the right hand winding thereof, right hand 110 armature and front contact, conductor 152, winding of relay 109 to ground at the normal contacts of relay 110. Relay 109 operates in this circuit. The operation of relay 208 also closes a circuit for operating the 115 associated vertical magnet 210 from ground at the normal contacts of relay 110, armature and front contact of relay 109, conductor 153, left middle armature and front contact of relay 208, right hand contact 224 of 120 the emergency key, to battery through the winding of magnet 210. The operation of magnet 210 prepares the contacts in the vertical row 201.

Should a subscriber in another vertical 125 group, as group 202, initiate a call at this stage, relay 228 will operate in a similar manner to that described for relay 206. However, since relay 207 operates simultaneously with the operation of magnet 210, 130

it will lock to ground at the left armature and front contact of relay 228 for purposes hereinafter described.

- When relay 208 operated, it also closed a circuit for relay 111 which is common to the group of horizontal links including links 217, 218, etc., as follows: from battery through the right hand winding of relay 111, right armature and back contact of relay 107, upper contacts 128 of the emergency key, right inner armature and front contact of relay 103, right hand contacts 129 of the emergency key, conductor 155, left outer armature and front contact of relay 208, left armature and contact of relay 117 to ground at the normal contacts of relay 110. The operation of relay 111 opens at its left armature and back contact the locking circuit for other relays similar to relay 111, thus preventing more than one selection of a horizontal link being made at a time. Relay 111 locks over a circuit traceable from battery, through the left hand winding, left armature and front contact of said relay, left armature and back contact of relay 116, winding of relay 117 to ground at the normal contacts of relay 110. Relay 117 operates in this circuit and opens at its left armature and contact the locking circuit for other relays similar to relay 111, thus preventing a plurality of calling lines from simultaneously gaining access to the same outgoing trunk through different horizontal links.
- Assuming that trunk 222 is idle then the relay 225 associated therewith is unoperated, and vertical magnet 215 will operate from battery, through its winding, lower armature and back contact of relay 225, right hand contacts 229 of the emergency key, left inner armature and front contact of relay 208, conductor 153, to ground through the left armature and front contact of relay 109. Relay 225 does not operate at this time since its winding is shunted by the above traced ground. When magnet 215 operates, it prepares the vertical row of contacts 203, and in conjunction with magnet 210 closes a circuit to operate one of the horizontal magnets, such as 212, which is associated with an idle horizontal link. Assuming that link 218 is busy, the magnet 213 and relay 114 associated therewith are in an operated condition. If, therefore, the next link 217, is idle a circuit will be closed from battery through the right hand winding of magnet 212, right armature and back contact of relay 113, right armature and front contact of relay 114, upper contacts 119 of the emergency key, right hand armature and front contact of relay 111, right hand armature and front contact of relay 117, upper contacts 120 of the emergency key, conductor 156, middle armature and front contact of magnet 210, lowermost armature and front

contact of magnet 215, conductor 157, to ground at the normal contacts of relay 121.

At the time the circuit for operating horizontal magnet 212 was closed, another circuit was established for energizing the slow operating relay 115 to start the release of the master circuit. This circuit is as follows: from ground at the middle armature and front contact of magnet 215, lowermost armature and front contact of magnet 210, conductor 158, upper contact 122 of the emergency key, to battery through the winding of relay 115. An interval of time elapses between the establishment of this latter circuit and the operation of relays 110 and 115 in order to allow the horizontal magnet 212 to operate.

When horizontal magnet 212 operates, the calling line 102 is connected through horizontal link 217 with trunk 222 and the cut-off relay 104 operates from battery, through its winding, sleeve conductor of the calling line, contacts of switch 200 to the sleeve conductor of the outgoing trunk which is temporarily grounded by means of the lower middle contacts of magnet 215. When relays 110 and 115 finally operate subsequent to the operation of a line vertical magnet and a trunk vertical magnet, the operating circuits for these latter magnets are broken. The vertical magnets 210 and 215 therefore release. However, the connection through the switch is held by means of horizontal magnet 212, which is locked from battery through both windings in series, winding of relay 113, contacts of switch 200 to the sleeve of the outgoing trunk which is grounded in any well known manner.

When relays 110 and 115 have operated, the holding circuits of vertical control relay 105 208 and horizontal control relay 111 are broken and these relays release, in turn releasing relays 109 and 117. The release of relay 117 removes the short circuit from around the winding of relay 113, which operates in series with horizontal magnet 212, thus rendering link 217 non-selectable by any other calling line. Relay 106 released as a result of the operation of cut-off relay 104. Relay 207, however, does not release if a call in another vertical group had been initiated as previously described, in which case relay 207 is locked to the left armature and front contact of a relay similar to relay 206.

The operation of relays 110 and 115 also removed the short circuit from around the winding of relay 225, which now operates from ground on the sleeve of the outgoing trunk, and renders trunk 222, busy to other calling lines. All the relays of the master circuit are now released and in condition to control the selection of another outgoing trunk.

If, while the above connection was in

progress, a calling subscriber, whose line terminates in another vertical group as group 202, had initiated a call, the relay 228 associated therewith would be operated and relay 207 would remain locked, after the first calling line had been connected to an outgoing trunk, as previously described. This insures an equitable distribution of calls among the several vertical groups since in this case relay 203 cannot again operate until the call waiting in group 202 has been completed through switch 200.

From the foregoing description it will be apparent that no two calling subscribers can interfere with each other, since but one connection through the switch 200 is completed at a time.

Emergency operation.

Under certain conditions, however, it may be desirable to allow more than one calling line to make selection through the switch 200. This would be the case where abnormal traffic conditions occur and a larger number of connections must be made than when the switch is functioning normally. In some instances, it may be necessary to remove the master circuit either for repair or for other reasons. Ordinarily in such cases a second master circuit would have to be provided to take the place of the one disabled, thus necessitating the use of costly duplicate apparatus which would be idle for comparatively long intervals. The invention has for one of its purposes, therefore, to prevent disruption of service under emergency conditions by providing a common control circuit which is at once efficient, comparatively simple and speedy in operation.

For this purpose an emergency key is provided. When a subscriber, as the subscriber at station 150, initiates a call and this key is operated, line relay 103 and relay 106 operate in the manner described under normal operation. The operation of relay 103 immediately closes a circuit for operating the particular vertical magnet, in this case, magnet 210 which is associated with the vertical row of contacts 201 in which the calling line appears. The circuit for this purpose is as follows, from battery, through the winding of magnet 210, left hand contact 224 of the emergency key, conductor 149, left hand contacts 108 of the emergency key, outer armature and front contact of relay 103, to ground at lower contact 105 of the emergency key. When relay 106 operates a circuit is closed to actuate the vertical magnet 215 associated with an idle trunk. This circuit is traceable from battery through the winding of magnet 215, lower armature and back contact of relay 225, left contacts 229 of the emergency key, conductor 148 to ground at the armature of relay 106. It will

be observed at this point that if a subscriber whose line terminates in another vertical group had simultaneously initiated a call, a different set of line vertical and trunk vertical magnets would also be operated.

As soon as magnets 210 and 215 operate a circuit is closed to energize slow operating relay 125 from battery through its winding, lower contact 122 of the emergency key, conductor 158, lowermost armature and front contact of magnet 210, to ground at the middle armature and front contact of magnet 215. While relay 125 is operating a circuit is closed to operate a horizontal magnet corresponding to an idle link. Assuming link 218 to be busy, a circuit is closed from ground at the normal contacts of relay 121, conductor 157, lowermost armature and front contact of magnet 215, middle armature and front contact of magnet 210, conductor 156, lower contacts 120 of the emergency key, left-hand contacts 129 of the emergency key, the inner armature and front contact of relay 103, lower contacts 128 and 119 of the emergency key, right-hand armature and front contact of relay 114, the armature and back contact of relay 113 to battery through the right-hand winding of magnet 212. After an interval when relay 121 operates as a result of the operation of relay 125, the circuit for holding magnets 210 and 215 operated is broken and these latter magnets release, in turn, releasing relays 121 and 125.

The connection through the switch 200, however, is held by means of horizontal magnet 212 which locks in series with the winding of relay 113 to the grounded sleeve conductor as described under normal operation. As soon as magnet 212 operates and locks, cut-off relay 124 operates, releasing relays 103 and 106. The release of relay 106 removes the short circuit from around the winding of trunk relay 225 which now operates from the grounded sleeve conductor and renders trunk 222 non-selectable by other calling lines.

From the foregoing description it will be apparent that more than one connection can be completed simultaneously through switch 200, and since the number of relays which function in such connection is comparatively small, the speed with which connections are made is relatively fast.

What is claimed is:

1. In combination, a selective switch, a non-interfering master control circuit for controlling the operation of said selective switch, means for taking said master circuit out of service, and means for automatically operating the switch thereafter without the use of any non-interfering master circuit.
2. In combination, a selective switch, a plurality of incoming lines, a plurality of

outgoing trunks, a non-interfering master circuit controlling the connection of said incoming lines with said outgoing trunks, a master circuit arranged to simultaneously control the extension of a plurality of connections through the switch, and manual means for replacing one of said master circuits by the other of said master circuits without disabling the switch.

11 3. In a switching device, a plurality of telephone lines, a plurality of connecting circuits, means for controlling the association of simultaneously calling lines with connecting circuits in a preferential order, and manual means for controlling the association of said simultaneously calling lines with connecting circuits in a non-preferential order.

15 4. In a switching device, a plurality of calling lines, a plurality of outgoing trunks, a plurality of connecting circuits, means for controlling the association one at a time of calling lines and connecting circuits, other

controlling means, and manual means for causing said other controlling means to control simultaneously the association of a plurality of calling lines with connecting circuits. 25

5. A switching device having vertical rows of contacts, lines appearing in certain of said vertical rows of contacts, trunks appearing in other of said vertical rows of contacts, circuits for extending said lines to said trunks, means for controlling the extension of simultaneously calling lines in a sequential order, other controlling means, and means for disabling said first mentioned controlling means to allow said simultaneously calling lines to be extended simultaneously under control of said second mentioned controlling means. 30 35 40

In witness whereof, I hereunto subscribe my name this 27th day of November A. D., 1923.

EDGAR H. CLARK.
